UNITED STATES PATENT OFFICE.

JOHN GOOD, OF BROOKLYN, NEW YORK.

INCLOSED FORCED-DRAFT BURNER.

1,231,152.

Specification of Letters Patent. Patented June 26, 1917.

Continuation in part of application Serial No. 822,813, filed March 6, 1914. This application filed December 8, 1916. Serial No. 135,721.

To all whom it may concern:

Be it known that I, JOHN GOOD, a citizen of the United States, residing in Brooklyn, New York, have invented the following-described Improvements in Inclosed Forced-Draft Burners.

The invention is a means of quickly obtaining high temperatures by the combustion of kerosene or other heavy liquid fuel within closed flame casings of narrow compass and consists in an organization and general arrangement of parts and operating means whereby the mere mechanical operation of the single actuating member may suffice to establish ignition and complete but non-explosive combustion in the closed passage, with promptness and certainty, and with a minimum expenditure of power and rapid rate of fuel combustion, and the invention still further and specially consists in the organization of the igniting agency whereby instant and reliable ignition can be obtained from electrical sources of low power, such for example as the ordinary magneto-generator as commonly used for gas-engine ignition, and it further consists in the means and arrangement adapting the said apparatus to be operated by hand power such as by a small crank, and in the special application of, and the mode of distributing, the combustion-supporting air to the flame in the closed passage, and in various other features of importance to the attainment of clean, quick and complete combustion of the fuel, especially heavy fuels, as stated, and all of which will become apparent to those skilled in this art from the following description.

The invention also is in part a continuation of my Patent No. 1207897 copending herewith, wherein combustion means of the same type has been claimed in combination with the vaporizer element of an internal combustion engine, in which relation it has particular utility.

In the accompanying drawings:

Figure 1 shows in side elevation one embodiment of the present invention, illustrating the flame passage and thing to be heated more or less diagrammatically;

Fig. 2 is a plan view of the parts shown in Fig. 1;

Fig. 3 is a central vertical section through the burner head of Figs. 1 and 2;

Fig. 4 is a cross section through the burner head of Fig. 3;

Fig. 5 represents in vertical section a more compact design of the burner head and an improved and simplified construction, including also the air-current dividing, and distributing member;

Fig. 6 is a cross section through the air entrance of Fig. 5;

Fig. 7 is a side elevation of a compact form of operating mechanism for the burner head in side elevation;

Figs. 8 and 9 are plan and end views respectively thereof;

Fig. 10 a cross-section on line X—X of Fig. 7; and

Figs. 11 and 12, sections of a further modified form of head.

Referring first to Figs. 1-4, the closed flame casing within which the combustion takes place includes the relatively narrow tube or passage 1 which opens into the confined space around the wall 2, representing the object to be heated, and beyond said object terminates in an open exhaust outlet 3 which may be assumed to be at some relatively remote or safe place for exhaust. The lateral entrance to this passage shown at 4 represents the entrance for another heating medium for heating the object 2 and for the case in hand, may be disregarded. When the said object 2 is the fuel vaporizer of an internal combustion engine, the opening 4 may represent the entrance for the engine exhaust as in the application referred to and when the exhaust is thus employed for heating the vaporizer, the throttle 5 will be understood to be closed, and vice versa, the passage 4 to be closed when the throttle 5 is open, so that the flame in the passage is always completely and effectively isolated from the surrounding exterior. The flame passage, however, may be variously constituted with this effect. The burner head which is also closed to the exterior atmosphere, comprises an air admis-

95
100

sion chamber 6 which is joined concentrically to the end of the flame tube and is relatively enlarged with reference to the diameter of the tube and formed with a tangential inlet 7, for the combustion-supporting air that is supplied to it. A nozzle cap 8, having substantially the same or slightly larger diameter than the flame tube is secured to or formed on the opposite side of 10 the said chamber 6, concentrically with the tube and constitutes an end closure for the latter and the flame tube. This nozzle cap 8 may be formed in one piece with, and carry, the liquid fuel receptacle 9 for the 15 burner head, as shown, which receptacle is supplied with fuel such as kerosene from a supply pipe 10. The liquid level therein is kept substantially constant by means of a float-controlled valve 11, or otherwise, and 20 the liquid is delivered to the cone-shaped interior of the cap by a liquid nozzle 12, and under the aspirating effect of an air or fluid-pressure nozzle 13, centrally mounted in the end of the cap. These nozzles are 25 adapted to project a finely atomized spray of the fuel liquid through the center of the air admission chamber and axially into the flame tube, and they work with excellent results for the purposes herein described when 30 their orifices are made with drills ranging in the standard sizes from No. 52 to 44, although these dimensions are of course subject to variation depending upon the combustion capacity desired. The upper wall 35 of the projecting nozzle cap 8 carries, permanently mounted therein, an electric spark igniter, constituted in the present case by a pair of single-pole plugs 14, having insulated electrodes 15 projecting inwardly and 40 downwardly toward the spray, with the spark-gap between them disposed directly in the path of the liquid spray, and preferably slightly offset above its central axis. The electrodes 14 are bent or shaped so that 45 their terminal portions diverge downwardly from the spark-gap, which formation serves to drain the liquid fuel impinging upon them away from the gap and thereby avoids the suppression of the spark that would 50 otherwise occur by a drop of liquid bridging the gap. This self-draining function of the electrode terminals, due to their divergence, tends to insure reliability of ignition especially with moderate currents and 55 short gaps. The longitudinal position of the spark-gap with reference to the spray nozzles is likewise a determining factor of the reliability of ignition, the proper position being substantially as illustrated in 60 Fig. 3. By following the relative dimensions indicated the apparatus herein described produces unfailing ignition of kerosene and heavier oils with a spark of a few milliamperes and less than a hundredth of

an ampere. The electrode terminals 15 will 65 be observed to protrude into the cap chamber from the centers of cavities in the upper wall of the cap or in the plug bodies which disposition of them is a further and desirable factor to the end of insuring reliable 70 ignition. The plug 16 in the upper wall of the cap 8 provides access to the liquid nozzle if it should clog and is normally closed tight.

The air nozzle 13 is connected by a pipe 17 75 to a source of air pressure in the present case, a positive or geared blower 18, the part 19 being an air chamber in the piped connection. The air admission chamber 6 is connected by pipe 20 to a rotary fan blower 80 21 and the two blowers 18 and 21 are driven by a common gear train 22 at respectively the proper speeds to spray the fuel and supply combustion-supporting air at the suitable relative rates to produce explosive proportions of fuel and air in the burner head 85 although not an explosive mixture. The fan blower 21 delivers air to the chamber in relatively larger volume and lower pressure than the air to the nozzle 13 and such air 90 joins the atomized liquid spray at a point close to but just in advance of the spark-gap, that is to say, where it does not dilute or distort the spray at its point of ignition, and it enters the spray uniformly on all sides 95 thereof. The ignition thus occurs in a place where the proportions of fuel and air cannot be or become explosive, and no explosion occurs because the complete mixture of the 100 combustion-supporting air with the spray occurs only after it has been ignited. In this way reliable and quiet ignition is obtained from unheated kerosene, with complete combustion indicated at the exhaust and without tendency to explode. As herein 105 used, the term "non-explosive" is intended to identify a steady combustion with a continuous flame, as distinguished from combustion which takes place as a series of pops, or explosions resembling pistol shots. 110

The same gear train which drives the air compressor apparatus also drives an electrical device which is connected to operate the igniter. In the present case, this device 115 is an ordinary magneto-generator 23, such as commonly employed for gasolene engines, and its gear ratio to the other apparatus in the train adapts it to produce an igniting current at any speed which will cause the latter to discharge a fuel spray into the flame tube. The operation of the gear train by the crank 24 thus automatically produces ignition of the fuel within the closed flame tube. The first spark ordinarily ignites the spray but it is preferred to continue the operation of the sparking current throughout the entire period of combustion. The shaft of the fan blower is shown 120 125

equipped with a fly-wheel 25. The use of separate blowers for the high and low pressure air supplies is preferred because of their economy of air pressure and ease of 5 operation. In the apparatus shown herein, an atomizing air nozzle pressure of say six or less pounds with fuel and air nozzles having orifices of the sizes stated, is sufficient to produce very satisfactory results, it being 10 understood that the pressure of the combustion-supporting air is governed according to the flow resistance of the flame passage to be overcome, which, however, and as above stated is open at its exhaust. Variation of 15 the operation of the crank produces corresponding variation of the intensity of combustion.

In the form of burner head shown in Fig. 5 the air chamber 6 and the nozzle cap 8 are 20 in one piece and the former is of less diameter than in Fig. 3 though larger than the adjoining flame passage. The combustion-supporting air introduced therein tangentially, is divided and distributed by a partitioning member 26 which is located centrally in said chamber and coextensive with the axial dimension thereof so that it extends from the nozzle cap portion to the entrance to the flame tube 1. This member 25 is formed, preferably, as a separate metallic part inserted into the air chamber from the flame tube end and appropriately seated therein or against the nozzle cap so as to preserve a central position. In its preferred form it consists of a star-shaped piece 30 of metal having its wings or walls arranged parallel with the direction of the spray and also thin so as to constitute the minimum obstruction to the forward motion of the latter. Such a member serves to divide the incoming combustion-supporting air into substantially equal portions surrounding the spray, and thereby promotes the formation in the flame tube of a certain stratified relationship of spray and air streams which is 35 highly efficacious in producing rapid mixture and combustion and the said member also independently helps the combustion by virtue, as I believe of the heated surfaces it 40 presents for vaporizing such particles of liquid fuel as may encounter it. Since all its surfaces are parallel or edge-on to the spray, it constitutes a vaporizing device without appreciable baffling or obstructing 45 effect. Other cellular bodies dividing the burner head or serving to produce a similar distribution of the incoming air on all sides of the ignited spray, without at the same time dislocating it also give improvement of 50 the same character either by virtue of their air dividing effect or air directing effect or by their vaporizing tendencies and as will presently appear. In this form of burner head the divergently related electrode termina- 55

nals 27 are also bent convergently to assist 65 in draining away the impinging liquid. Also the liquid nozzle is equipped with an adjustment valve 28.

Figs. 11 and 12 illustrate a burner head 70 similar to that of Fig. 5 provided with a modified form of air distributing member which consists of a perforated sleeve 29 centrally disposed in the air admission chamber 6 just in advance of the spark-gap and adapted to divide the incoming air current 75 into a multiplicity of small air jets around the spray, but none of them striking the spray near the spark-gap. Such a distributor may be employed by itself with similar effect to that of the star-piece above described or may be used in conjunction with the star-piece 26 placed inside of it, and is so shown.

Figs. 7 to 10 illustrate the unit construction of operating apparatus for any one of 85 the types of burner heads above described, the same being adapted to be actuated by a crank handle 30 or a small electric motor, to supply simultaneously the spraying pressure, combustion-supporting air and igniting current. It consists of the two blowers, 90 of the fan and positive types respectively, and a magneto-generator, all mounted on a single base or bracket and interconnecting gearing of the proper speed ratios to produce automatic ignition and complete, non-explosive combustion in the flame tube. The pipe connection 31 from the fan blower 32 and the pipe 33 from the high pressure blower or pump 34 are both desirably flexible, as also is the electric cable 35 which 100 connects the electrical device or magneto-generator 36 to the spark-plugs, so that the burner head need not hold a fixed position with respect to its operating apparatus. 105

The casing of the fan blower 32 is formed or cast in one piece with a horizontal shelf or plate 37, which serves as a base for the other parts of the operating apparatus, the magneto-generator 36 being mounted on the far side of this base and the high pressure or positive blower 34 on the upper part of the fan casing at one end of the generator. 110 In this position its operating shaft 41 extends between the upper parts of the blower and generator to the opposite end of the base 37 where the group of driving gears is located. The latter gears are journaled in the upstanding bracket 38 which is secured to the corner of the base 37 and carries also the journal for the internal gear 40, to which crank 30 is applied. The drive shaft 41 of the positive blower is journaled partly in its own blower casing and partly 115 in the bearing 42 which projects from the upper part of the fan casing and it is driven by its pinion 43 meshing with the upper part of the internal gear 40. The armature 120

- shaft 44 is parallel with the shaft 41, and driven by its pinion 45 meshing with the lower part of the internal gear 40. The shaft 44 carries at an intermediate point on 5 the generator side of the bracket 38, a helical gear 46 driving a smaller helical pinion 47 on a cross-shaft 48, and the end of this latter shaft carries a spur gear 49 driving the spur pinion 50 of the fan blower shaft.
- 10 The latter shaft is journaled in the fan casting. The specific construction of the fan and positive blowers and of the generator may be as desired and is not material to this invention, and it will be understood that in 15 the arrangement described the rotation of the gear 40 drives each member of the group at the appropriate speed to operate the burner properly and as already explained. The flexible offtake 31 from the fan blower 20 and the similar offtake 33 from the positive blower are both arranged at the same end of the assemblage and the electrical cable 35 is conveniently led off also from the same end, so that the crank handle 30 may thus be disposed in a desirably projecting relation for 25 convenient operation.

It may be stated in conclusion that the several parts of the invention as illustrated are so arranged that the first turn, or even 30 less than a single turn, of the operating crank is sufficient to establish instant flame in the closed flame tube and that the velocity of crank motion controls the rate of fuel delivery and hence the rate of combustion, 35 which may be as rapid as desired within the capacity of the apparatus.

Claims:

1. A forced-draft combustion device adapted to burn kerosene and like fuel comprising 40 a closed flame-confining tube or passage having an exhaust opening at one end and a burner head at the opposite end, fluid pressure means in said head for atomizing a spray of the liquid fuel into said passage in 45 an initially cold condition, an electric igniter including electrode members directly intercepting said spray and divergent downwardly from the spark-gap between them whereby liquid fuel impinging thereon 50 drains away from the gap, and means for introducing combustion-supporting air under pressure into said burner head and into contact with said spray at a point thereof which is close to but where such air does 55 not dilute the spray at the spark-gap, in combination with means for simultaneously supplying fluid pressure to said atomizing means and combustion-supporting air to said burner head in a predetermined and 60 substantially constant relation to render said spray ignitable by the spark in an initially cold condition and adapted to burn non-explosively and with substantially complete combustion in said closed passage.
- 65 2. A forced-draft combustion device adapt-

ed to burn kerosene and like fuels comprising a closed flame passage having an exhaust opening at one end and a burner head at the opposite end, fluid pressure means in said head for atomizing a spray of the liquid fuel into said passage, an electric spark igniter mounted in said head with its spark-gap disposed in the direct path of the spray and slightly offset from the axis of said spray and including electrode members divergent away from the spark-gap between them whereby the liquid fuel impinging thereon drains away from the gap, and means for introducing combustion-supporting air under pressure into said burner head and into contact with the spray without diluting the same at the spark-gap, in combination with means for simultaneously supplying fluid pressure to said atomizing means and combustion-supporting air to 70 said burner head in a predetermined and constant relation to render said spray ignitable by the spark in an initially cold condition and adapting the same to burn non-explosively and with complete combustion 75 in said closed passage.

3. A forced-draft combustion device adapted to burn kerosene and like fuels comprising a closed flame-confining passage having an exhaust opening at one end and a burner head at the opposite end, fluid pressure means in said head for atomizing a spray of liquid fuel into said passage, an electric igniter mounted in the burner head including electrodes, one or both of which protrudes inwardly from a recess or cavity in the upper part of said head and into the direct path of said atomized spray whereby the spark-gap directly intercepts said liquid spray and means for introducing combustion-supporting air under pressure into said burner head and into contact with said spray at a point where it does not dilute the same at the spark-gap, in combination with means for simultaneously supplying fluid pressure to said atomizing means and combustion-supporting air to said burner head in predetermined relation to render said spray ignitable by the spark in an initially cold condition and adapting it to burn non-explosively in said closed passage.

4. A forced-draft combustion device for burning kerosene and like fuels comprising a closed flame-confining tube or passage having an open exhaust outlet at one end and a burner head at the opposite end, fluid pressure means in said head for atomizing a spray of liquid fuel into the passage, an electric spark igniter mounted in said head with its spark-gap disposed in the direct path of the spray and including an electrode terminal which protrudes into the spray from a cavity in the wall of the burner head, and means for introducing combustion-supporting air under pressure into said 120

- 125 130

- burner head, uniformly round about said spray but not diluting the same at the spark-gap, in combination with means for simultaneously supplying fluid pressure to said atomizing means and combustion-supporting air to the spray therefrom in predetermined relation to render said spray ignitable by the spark in an initially cold condition and to burn non-explosively in said passage.
10. 5. A forced-draft combustion device for burning kerosene and like fuels comprising a closed flame-confining tube or passage having an outlet at one end and a closed burner head at the other containing means for atomizing liquid fuel into said flame tube, an electric spark igniter intercepting the atomized spray and an entrance for combustion supporting air, said spark igniter and air entrance being relatively disposed so that the air stream from the latter does not disturb the spray at the location of the spark from the former, in combination with a cellular air-current distributing member mounted in said head directly in advance of the location of the spark-gap and means for simultaneously operating said atomizing means and supplying air under pressure to said air entrance in predetermined and constant relation to permit spark ignition of said fuel spray in an initially cold condition and adapted to produce complete non-explosive combustion thereof within said closed passage.
6. A forced-draft combustion device for burning kerosene and like fuels comprising a closed flame tube or passage having an outlet at one end and a closed burner head at the other containing means for atomizing liquid fuel into said flame tube, an electric spark igniter intercepting the atomized spray and an entrance for combustion-supporting air surrounding all sides of the atomized spray therein immediately in advance of the igniter, in combination with cellular, air-current-dividing and distributing means mounted in said head and coinciding with the position of the said air entrance thereto and means for simultaneously operating said atomizing means and supplying combustion-supporting air to said air entrance in a predetermined and constant relation to permit spark ignition of said fuel spray in an initially cold condition and operating to produce complete, non-explosive combustion thereof within said closed passage.
7. A forced-draft combustion device for burning kerosene and like fuels comprising a closed flame confining tube having an open exhaust outlet at one end and a closed burner head at the opposite end comprising a relatively enlarged air admission chamber surrounding the central longitudinal axis of the flame tube and adapted to permit inward flow of air from all sides of said axis, a nozzle cap in rearward projecting relation to said chamber and of less diameter than the said chamber and forming an end closure for said tube and chamber, nozzles carried by said cap for atomizing liquid fuel through said chamber and into said flame tube and an electric spark igniter mounted in said cap between the fuel nozzle and the air admission chamber, and directly intercepting the spray from said nozzle, in combination with means for simultaneously operating said atomizing means, and supplying air under pressure to said air entrance in a predetermined and constant relation to permit spark ignition of said fuel in an initially cold condition and adapting the same to burn non-explosively within said flame tube.
8. A forced-draft combustion device for burning kerosene and like fuel comprising a closed flame passage having an outlet at one end and a closed burner head at the other containing means for atomizing liquid fuel into said flame tube and including a liquid fuel nozzle a constant-level liquid fuel supply receptacle connected thereto and a fluid pressure atomizing nozzle in aspirating relation to said liquid nozzle, an electric spark igniter intercepting the spray from said nozzle, an entrance for combustion-supporting air surrounding all sides of the said spray and in advance of the said igniter and admitting said air at a point where it does not dilute the spray at the igniter, and means for simultaneously supplying fluid pressure to said atomizing nozzle and combustion supporting air to said air admission entrance in a predetermined and substantially constant relation rendering said spray non-explosively ignitable by said spark in an initially cold condition.
9. An automatically igniting forced-draft combustion device burning kerosene and like fuels, comprising a closed flame-confining tube or passage, means for atomizing liquid fuel into said flame tube, an electric spark igniter intercepting the atomized spray therein and an air entrance for combustion supporting air surrounding the spray, said igniter and air entrance being relatively disposed so that the air stream from the latter does not dilute the spray at the location of the spark, in combination with means for simultaneously operating said atomizing means and supplying air under pressure to said air entrance in a predetermined and constant relation, an electrical device for operating said igniter, and a single operating member conjointly controlling said atomizing and air supply means and the said electrical device, and producing non-explosive spark ignition of said fuel within said closed passage.
10. An automatically igniting, forced-draft combustion device burning kerosene and like fuel comprising a closed flame-confining tube or passage having an outlet

- at one end and a closed burner head at the other containing means for atomizing the liquid fuel with air, an electric spark igniter intercepting the atomized spray and an entrance for combustion-supporting air surrounding all sides of the atomized spray, said spark igniter and air entrance being relatively disposed so that the air stream from the latter does not disturb the spray 5
- 10 at the location of the spark, in combination with air compressing apparatus and a magneto-generator connected therewith by suitable gearing adapted to operate the air supplying means in predetermined constant relation to permit spark ignition of the fuel spray in an initially cold condition, and manually operated means for conjointly operating said generator and compressing apparatus to produce complete and non-explosive combustion within the flame tube. 15
11. An automatically igniting, forced-draft combustion device burning kerosene and like fuel comprising an air nozzle for atomizing the liquid fuel, an electric spark igniter intercepting said atomized spray, an entrance for combustion-supporting air, said igniter and air entrance being relatively disposed so that the air stream from the latter does not disturb the spray at the location 20 of the spark-gap, in combination with separate air-compressing apparatus for said nozzle and air entrance respectively, a magneto-generator for operating said igniter and a single means for conjointly operating said air-compressing apparatus and generator. 25
12. An automatically igniting, forced-draft combustion device for burning kerosene and like fuel comprising a liquid fuel 30 nozzle supplied with the liquid fuel from a constant-level receptacle, an air nozzle adapted to aspirate and atomize fuel from said nozzle, an electric spark igniter having divergent, self-draining electrodes directly intercepting said spray, an air entrance for combustion-supporting air, said igniter and air entrance being relatively disposed so that the air stream from the latter does not dilute the spray at the spark gap, in combination 35 with air compressing apparatus arranged to supply said air nozzle and air entrance with air in predetermined constant proportions adapting the atomized fuel spray to ignite in an initially cold condition, a magneto-generator, gearing connecting the same with the said compressing apparatus and a single, manually operable member for conjointly driving the same. 40
13. An automatically igniting, forced-draft combustion device burning kerosene and like fuel, comprising a flame passage, a liquid nozzle connected to a constant level supply of the liquid fuel, an air nozzle in aspirating and atomizing relation thereto 45 adapted to project a spray of liquid fuel into the passage, an electric spark igniter intercepting said atomized spray, an entrance for combustion-supporting air surrounding the spray therein, said igniter and air entrance being relatively disposed so that the air stream from the latter does not disturb the spray at the location of the spark from the igniter in combination with a positive blower connected with said air nozzle, a rotary fan blower connected with said air entrance, said positive and fan blowers being geared together to supply air to said flame passage in predetermined and constant relation adapting the said fuel spray to be spark-ignited within said passage, an electrical device connected to operate the igniter and a single means for operating said blowers and device whereby combustion is established and continues non-explosively in said passage. 50
14. An automatically igniting, forced-draft combustion device for burning kerosene and like fuels, comprising a closed flame passage having an open exhaust outlet at one end and a closed burner head at the opposite end, fluid pressure means in said head for atomizing a liquid fuel spray into said passage, an electric igniter including divergently related, self-draining electrode members directly intercepting said spray, an entrance for combustion-supporting air surrounding the spray close to and just in advance of the igniter, in combination with means for conjointly operating said fluid pressure means and supplying combustion-supporting air to said air entrance in predetermined and constant relation adapting said spray to be spark ignited in an initially cold condition, an electrical device for operating said igniter and a single member for conjointly operating said pressure, air supplying means and said electrical device to produce complete and non-explosive combustion of the fuel in the flame passage. 55
15. An automatically igniting, forced-draft combustion device for burning kerosene and like fuels, comprising a closed relatively narrow flame-confining tube having an open exhaust at one end and a closed burner head at the other containing fluid pressure means for atomizing a spray of the liquid fuel into said passage, an electric igniter mounted in the head and having electrode terminals extending downwardly from the upper wall of said head and directly intercepting the said spray, and an air entrance for combustion-supporting air surrounding said spray immediately in advance of the igniter in combination with a star-shaped partitioning member longitudinally coinciding with the entrance of the combustion-supporting air to said flame passage, means for conjointly supplying fluid pressure to said atomizing means and air to said air entrance in predetermined relation. 60

and at different pressures adapting the fuel to be spark ignited in the casing or passage and to burn non-explosively therein, and an electrical device for operating the igniter.

5 16. In apparatus of the class described, a closed flame tube having an open outlet for products of combustion at one end, and a burner head at the other end comprising an air entrance chamber of greater diameter 10 than said tube concentrically connected thereto, a nozzle cap member of substantially the same diameter as said flame tube connected to the air chamber in substantial alinement with the flame tube, fuel spraying 15 means and an electrical spark igniter in said cap member, and a float-controlled supply receptacle for said fuel spraying means carried by said cap member, in combination with means for simultaneously supplying 20 air under pressure to said chamber and operating said spraying means and igniter.

17. Automatically igniting, forced-draft combustion apparatus comprising a closed burner head having a liquid fuel nozzle, an air atomizing nozzle, an entrance chamber 25 for a forced supply of combustion-supporting air and an electric spark igniter, all adapted to produce ignition and continuous combustion in said closed burner head, in combination with a fan blower, a positive blower, and a sparking current producer, all grouped on a single base or support, connections from the same to said air entrance, 30 air nozzle and igniter respectively, and a single operating wheel geared to all of said 35 apparatus.

18. Automatically igniting combustion ap-

paratus comprising a closed burner head having a liquid fuel nozzle, an air atomizing nozzle, an air entrance chamber for a forced 40 supply of combustion-supporting air and an electric spark igniter, all adapted to produce ignition and continuous combustion in said head, in combination with air compressing apparatus and a sparking current producer, 45 mounted on a single base or support and having flexible connection from the same to said air entrance, air nozzle and igniter respectively.

19. A mechanically operated, combustion 50 device for automatically igniting and burning liquid fuel in closed passages of narrow compass comprising, a liquid fuel supply chamber, a flame tube having an open exhaust at one end and a closed burner-head 55 at the other, said burner-head containing a fuel nozzle supplied from said chamber, an electric spark igniter and double inlets for air, one of said inlets operating to suck and spray liquid fuel from said nozzle in proportion to the velocity thereof and the other to supply all the air requisite for the combustion of the spray in said flame tube, in combination with an operating assemblage 60 for said burner-head including air-compressing and electric apparatus, respectively and permanently connected to said inlets and igniter, and a single rotary drive member for said apparatus adapted solely by its rotation to start and maintain said 65 burner-head in operation.

In testimony whereof, I have signed this specification.

JOHN GOOD.
